UNITED STATES PATENT OFFICE.

WALTER GUTTMANN, OF MÜLHEIM-ON-THE-RUHR, GERMANY.

PLASTER.

977,730.

Specification of Letters Patent.

Patented Dec. 6, 1910.

Application filed March 15, 1910. Serial No. 549,420.

To all whom it may concern:

Be it known that I, WALTER GUTTMANN, doctor of medicine, of Mülheim-on-the-Ruhr, Germany, a subject of the King of Prussia, (and whose post-office address is 38 Adolfstrasse, Mülheim-on-the-Ruhr, Kingdom of Prussia, German Empire,) have invented a new and useful Plaster, of which the following is a specification.

10 My invention relates generally to medical plasters of any kind, but more specifically comprises an improved form of adhesive plaster.

15 The object of my invention is to produce a plaster which shall not have its effective area or medicinal properties substantially reduced, and which may yet be more easily, expeditiously and painlessly removed after use, than is possible with the ordinary adhesive plaster.

20 The ordinary adhesive plaster has a surface of active material which becomes closely attached to the skin of the patient and consequently causes considerable pain in its removal because it creates a continuous tearing action along the surface of the skin during the operation of removal. This tearing action begins as soon as one edge of the plaster is lifted from the body of the patient and 25 continues without interruption during the removal operation, for which a steady pull of much force is often required. I avoid this difficulty by substituting for the continuous adhesive surface of the usual form of plaster, 30 a surface divided into a large number of small separate areas of such adhesive material, preferably quadrilateral in form, which are divided one from the other by fine border lines of non-adhesive material.

35 40 The best form at present known to me embodying my invention is illustrated in the accompanying sheet of drawings in which,

Figure 1 is a plan view on an exaggerated scale of a plaster made according to my invention, and Fig. 2 is a cross section on line 45 2-2 of Fig. 1.

Throughout the drawings like reference letters indicate like parts.

45 50 *a* is the back of the plaster formed of cloth or other strong flexible material, and *b* the active material of adhesive nature, these parts being of usual or any desired character. The adhesive surface is divided, according to my invention, into a large number 55 of small areas, *d*, preferably of quadrilateral shape as shown. The dividing lines *c* are

formed or some non-adhesive material such as thread, or fine cords or ribbons. These threads etc. are permanently sunk in the surface of the adhesive material to an extent or 60 depth which leaves only their upper surfaces exposed. These threads etc. are usually arranged in two sets, the threads of each set being substantially parallel and widely spaced apart so that they cover but a small 65 percentage of the surface of the plaster, and the threads of one set running crosswise of those of the other set. Preferably this is done by forming the two sets of threads into a fine, open mesh net, as shown in the drawing, and partially sinking said net into the 70 surface of the plaster.

75 In operation the effective surface of the plaster is not substantially reduced, but it is divided into a large number of separate areas of adhesive material which breaks up the continuity of the tearing action when the plaster is pulled away from the skin, whatever the direction in which the pull is applied. This materially reduces the pain 80 of the removal operation and facilitates it in every way.

85 My invention is sharply differentiated from the old use of gauze or similar fabric which is temporarily laid over the face of adhesive and other plasters before use to prevent them from sticking together or to other objects during storage, transportation and handling, and which must always be removed before the plaster is put into use. 90 This old form of gauze forms no permanent part of the plaster as an operative entity and in fact prevents it from operating at all, since it completely covers up the active 95 material and the plaster has no adhesive or medicinal effect if applied without first removing the gauze. In fact this old form of gauze is usually employed in packing and preparing for shipment plasters of my invention to perform its old function, and is 100 pulled off before using the plaster, all in exactly the same way as with the old form of plaster.

105 Having, therefore, described my invention, I claim:

1. The combination with an adhesive plaster of a series of threads spaced apart from each other and running across the face thereof and permanently sunk therein to a depth which leaves only their upper surfaces 110 exposed.

2. The combination with an adhesive

2
plaster of an open mesh net of fine thread extending over the face of the active material and permanently sunk therein to a depth which leaves exposed only the upper surfaces of the threads forming the net.

3. The combination with an adhesive plaster of two sets of threads permanently sunk in the face of the adhesive material to a depth sufficient to leave only their upper surfaces exposed, the threads of each set being widely spaced apart, and those of one set running crosswise of those of the other set.

4. As an article of manufacture an adhesive plaster having its active face divided into a great number of small quadrilateral portions separated by narrow border lines of non-adhesive material by which the plaster may be removed.

20
In testimony whereof I have hereunto set my hand in presence of two subscribing witnesses.

WALTER GUTTMANN. [L.S.]
